CLAIM

The ornamental design for an outsole for a shoe, as shown and described.

DESCRIPTION

FIG. 1 is a bottom perspective view of an outsole for a shoe in accordance with the new design;

FIG. 2 is a bottom view thereof;

FIG. 3 is a left side view thereof;

FIG. 4 is a right side view thereof;

FIG. 5 is a rear view thereof; and,

FIG. 6 is a front view thereof.

The broken lines shown in the arch area of FIGS. 1–4 represent boundaries of the design with the lines themselves and the areas within them forming no part of the claim.
